UNITED STATES PATENT OFFICE.

THEODORE M. FOOTE, OF ALLSTON, MASSACHUSETTS, ASSIGNOR TO NATIONAL BINDING MACHINE CO., OF BOSTON, MASSACHUSETTS, A CORPORATION OF MAINE.

STRIP-SERVING APPARATUS.

1,149,144.

Specification of Letters Patent.

Patented Aug. 3, 1915.

Application filed February 27, 1911. Serial No. 611,224.

To all whom it may concern:

Be it known that I, THEODORE M. FOOTE, a citizen of the United States, and a resident of Allston, in the county of Suffolk and 5 State of Massachusetts, have invented an Improvement in Strip-Serving Apparatus, of which the following description, in connection with the accompanying drawings, is a specification, like characters on the 10 drawings representing like parts.

This invention relates to strip serving apparatus and particularly to those in which the strip is drawn manually from a roll or package by the operator.

15 In order that the principle of the invention may be readily understood, I have disclosed certain embodiments thereof in the accompanying drawing, wherein—

Figure 1 is a side elevation of a strip serving apparatus embodying my invention; Fig. 2 is a plan view of the construction shown in Fig. 1 with parts being broken away; Fig. 3 is a plan view, partially in section, upon the line 3—3 in Fig. 1, of the forward portion of the apparatus; Fig. 4 is a 20 front elevation with parts broken away of the apparatus shown in Fig. 1; Fig. 5 is a vertical section on the line 5—5 of Fig. 4 of the forward portion of the apparatus and 25 representing the strip as positioned during non-service; Fig. 6 is a similar view representing the strip as positioned during service; Fig. 7 is an enlarged vertical sectional view of the moistening and coöperating portion of the apparatus, parts being omitted for clearness; Fig. 7^a is a plan view of a detail of the apparatus; Fig. 8 is a vertical 30 section of the forward portion of a modified form of strip serving apparatus, the parts 35 being in the position assumed during non-service; Fig. 9 is a similar view but representing the parts as positioned during service; Fig. 10 is a vertical sectional view of the 40 apparatus shown in Fig. 8, the moistener roll being omitted; and Fig. 11 is a plan view 45 of the construction shown in Fig. 9.

Referring more particularly to the drawings and first to that form of my invention shown in Figs. 1 to 7 inclusive, the base of 50 the apparatus is represented at 1, it having formed therewith or secured thereto a roll or package holder 2, here shown as a substantially cylindrical casing having secured in the fixed vertical face thereof a threaded spindle 3 adapted to receive thereon the

strip roll 4 and a cap or closure 5 having an enlarged central hole for the passage of said spindle and finger holds 6—6 struck up from the body of said cap or closure 5, so that when the nut 7 upon the spindle has 60 been removed by one hand of the operator the hand holds 6 may be grasped by the fingers of his other hand and the cap be readily removed. The adjustment of the nut 7 serves to tension the strip roll. If desired, 65 I may provide any suitable means peripherally engaging the roll and coöperating to tension it. I have here shown a weighted lever 8 pivoted at 9 in a slit in the casing, the outer end of said lever forming a handle 10 by means of which the lever may be 70 removed from tensioning position for insertion of a fresh roll or other purpose. The strip roll 4 is preferably composed of paper or cloth previously gummed upon one 75 face and herein upon the inner face thereof. In certain forms of my invention, however, the strip may be ungummed and a suitable adhesive may be applied thereto during draft upon the strip. In the present form 80 of my invention I provide suitable means for applying moisture and preferably water to the previously gummed face of the strip, as it is drawn from the strip roll. For that purpose I have here shown positioned upon 85 the base 1 a removable tray or reservoir 11 positioned between suitable lugs 12 at its front and rear and at its sides between preferably metallic upright plates 13 secured by screws 14 or otherwise to the base and 90 notched or otherwise fashioned at 15 for the reception of a moistener here shown as a roll 16. Formed with or secured to the plates 13—13 is a transverse plate 17, whose upper edge is serrated or sharpened as indicated at 18 to form a severing edge or blade. It will be noted that the said strip severing edge is, in this form of my invention, 95 positioned to the rear of the axis of the moistening roll 16, although preferably said 100 strip severing edge overhangs the said roll. The described construction permits the more ready removal of the moistener roll. Any other suitable strip severing device may be employed and located as desired.

105 An important feature of my invention is the provision of means for presenting and applying to the previously gummed face of the strip a mere film of water or other suitable gum moistening liquid and coöperat- 110

ing means for so pressing the strip onto the moistener that the liquid film is forced substantially simultaneously into the very substance of the gum, so that it is immediately softened and rendered effective for securing the strip in its intended position. In carrying out this feature of my invention, I preferably form the peripheral surface 19 of the rotatable moistener as a non-absorbent surface and preferably of metal, such as sheet brass. Such a surface takes up from the water or other liquid in the tray 11 a thin layer or coating. In order that this layer may be reduced to the condition of substantially a film, I provide means contacting both with the ends of the roll and with its peripheral surface to discharge therefrom all surplus moisture, so that to the gummed surface of the strip is presented merely a thin film of moisture. To that end, I provide a scraper 20 having an edge 21 bearing upon the peripheral face 19 of the moistener. The said scraper is provided with arms 22 by which it is pivoted at 23 in the side plates 13, so that the scraper rests by its own weight against the moistener as illustrated most clearly in Figs. 5 and 6. To contact with the ends of the moistener I provide spring plates 24 suitably secured as indicated in Fig. 3 to the side plates 13, the lower edge 25 of each plate bearing as indicated upon the end of the moistener roll between its spindle and its peripheral surface 19. In this manner, and as most clearly indicated in Fig. 7, the excess moisture is removed not only from the peripheral surface, but from the ends of the roll, so that a substantially true film of liquid is presented to the gummed face of the strip. It will be noted that the spring plates 24 are at the rising side of the moistener. The said plates may be pressed into contact with the moistener in any suitable manner. Preferably I provide means whereby the strip as it is drawn upon by the operator is thereby pressed into contact with the moistener roll so as to enforce proper moistening thereof. Preferably also I provide means whereby after strip severance the free end of the strip is removed from contact with the moistener. In that embodiment of my invention herein selected for illustration, I have provided a rocking or pivoted frame composed of arms or side members 26 pivoted upon a transverse spindle or rod 27, which at its ends is recessed for the reception of axial screws 28 by removal of which the frame may be removed from the apparatus. Upon the lower ends of said arms 26 I preferably pivot a metallic or other roll 29, under which the end 30 of the strip passes and also provide a tie rod 31, under which and the spindle 27 the strip passes. Upon the front end of the side arms I loosely mount a preferably metallic roll 32 consti-

tuting a presser to compel contact of the gummed face of the strip with the moistener when the strip is drawn upon for use. Preferably this roll is provided with a corrugated surface shown most clearly at 33 in Fig. 4. By ribbing or corrugating or otherwise interrupting the said surface, I prevent the flow of water along said roll and thence onto the strip. In the operation of the device, water may accumulate upon some portion of the rocking frame and were the surface of the roll 32 not interrupted as described, this water might come in contact with the surface of the strip. In order further to guard the strip from the liquid in the tank 11, and also from liquid that may be discharged from the moistener 19 or that may run back from the free end of the strip when elevated, I provide a preferably metallic shield 34, which may have an upturned rear end and is provided with an upturned, thin front edge 34' preferably serrated as indicated in Fig. 7. The rear portion of the shield is cut away at intervals as represented at 35 and is also perforated as indicated at 36. The strip passes between the thin edge 34' and the pivotal rod 27. The said strip does not contact with the shield flatwise of the latter, but only with said thin forward edge 34'. When the strip is drawn upon for use the upward pressure of the strip upon the roll 29 forces the presser roll 32 downwardly sufficiently close to the moistener roll to compel intimate contact of the strip with the moistener, thereby forcing the film of moisture into the very substance of the gum and quickly moistening it. After a suitable length of strip has been drawn from the roll and moistened as described the strip is then deflected into engagement with the severing edge 18 and there severed. The rocking frame carrying the rolls 29, 32 yields to permit this action. Preferably I also provide means, such as a spring or springs 37, secured to one or both of the plates 13 to elevate the frame into the position indicated in Fig. 5 after severance of the strip. The tension of said spring or springs may be adjusted by engaging one end thereof with the desired pin or pins 38. It is, of course, evident that the pivoted frame may be suitably weighted to effect the same result. It is apparent that in this embodiment of my invention the strip is severed at a point somewhat in advance of the rear edge of the moistened area. Therefore when the free end of the strip is elevated as indicated in Fig. 5, there is thereon some moisture, which under some conditions of use may tend to flow back down the face of the strip to the guard 34. Any such moisture will be intercepted by the edge 34' and be discharged from the lower face of said guard 34 into the tank 11. If, however, moisture from any source should find its way

to the upper face of the guard 34, it would be discharged through the openings 35 and perforations 36. By providing the edge 34' with serrations I prevent any tendency of the strip adhering objectionally to said edge during periods of non-use. In other words, any adherence will be merely to the tips of the serrations and the strip may readily be freed therefrom by a slight forward pull.

10 Moreover, the contact of the edge 34' with the strip insures the positioning of the strip from contact with the moistener substantially as indicated in Fig. 5.

In Figs. 8 to 11 inclusive, I have represented a somewhat different form of my invention. Therein I provide any suitable moistening device, such as a roll 39 which may be similar in all respects with the moistener roll 16. Upon suitable standards 40 I 20 pivot, as indicated at 41, a frame composed of side members 42 having a top connecting strip 43, the front edge 44 of which is suitably sharpened or serrated to provide a strip severing edge. Loosely mounted between the arms 42 are pivoted two rolls 45, 46 over and under which the strip passes, as indicated in Figs. 8 and 9. Encircling the pivot 41 of the frame and attached respectively to the frame and to one of the standards 40 is a spring 47 tending normally to hold or maintain the frame in the elevated position indicated in Fig. 8. The standards are provided with an extension 49 constituting a shoulder or stop with which said frame contacts when elevated and to limit its backward movement. When the strip is drawn upon for use, its contact with the rear surface of the roll 45 depresses the frame as indicated in Fig. 9, so that the roll 46 30 presses the strip into contact with the surface of the moistener in substantially the manner described in connection with Figs. 5 and 6. The spring or springs 47 yield to permit this depression of the frame, and 45 after a suitable length of strip has been drawn from the roll, it is then deflected upwardly against the severing edge 44, which when the arm brings up against the shoulders 49 severs the strip. The free end of the 50 severed strip remains elevated or separated from the moistener, as indicated in Fig. 8.

It is evident from the foregoing description that only a sufficient amount of moisture is presented to the gummed surface of the strip to effect the proper moistening thereof. All excess moisture, which would result in undue wetting and weakening of the strip, is excluded or discharged from the face of the moistener before it is presented to the strip. The strip itself is positively pressed into contact with the suitably moistened surface of the moistener, and thereby the gum is instantly softened. After strip severance, the free end of the strip is removed from contact with the moistener.

Having thus described certain illustrative embodiments of my invention, I desire it to be understood that although specific terms are employed, they are used in a generic and descriptive sense and not for purposes of limitation, the scope of the invention being set forth in the following claims.

Claims:

1. A strip serving apparatus comprising in combination, a strip roll support from which a strip may be drawn by the hand of the operator, a non-absorbent moistener having means to present a thin film of liquid to the strip and to prevent the presentation of liquid in excess of said film, strip severing means, and a strip presser actuated by draft upon the strip to press the strip, when drawn upon, into intimate engagement with said liquid film. 75

2. A strip serving apparatus comprising in combination a strip roll support, a non-absorbent moistener having means to present a thin film of liquid to the strip, strip severing means, and means actuated by service draft upon the strip to press the strip into intimate engagement with said liquid film and upon strip severance positively to effect separation of the strip and moistener. 80

3. A strip serving apparatus comprising in combination a strip roll support, a rotatable moistener co-operating therewith having a non-absorbent periphery, means to present a thin film only of liquid to the strip, means to press the strip into contact with the moistener during strip service, and means to separate the strip from the moistener after strip service. 90

4. A strip serving apparatus comprising in combination, a strip roll support, a moistener, a severing blade against which the strip may be manually drawn for severance, and means controlled by strip service and constructed and arranged to press the strip into contact with the moistener during strip service, and to remove it therefrom after strip service into strip grasping position, with its free end supported out of contact with the severing blade. 100

5. A strip serving apparatus comprising in combination, a strip roll support, a moistener, a severing blade against which the strip may be manually drawn for severance, and a pivoted frame controlled by strip service and having a pressing member to engage the strip and constructed and arranged to press the strip into contact with the moistener during strip service and to lift the strip therefrom after strip service into grasping position with its free end out of contact with the severing blade. 110

6. A strip serving apparatus comprising in combination, a strip roll support, a moistener, strip severing means above and in the rear of the moistening point, and a mov- 120

able strip presser constructed and arranged to engage the strip and to press it during service into contact with the moistener, and to position the free end of the strip after severance in grasping position between the moistener and the severing blade.

7. A strip serving apparatus comprising in combination a strip roll support, a non-absorbent moistener having means to present a thin film of liquid to the strip, strip severing means, a movable presser actuated by service draft upon the strip to press the strip into intimate engagement with the liquid film, and co-acting means between which and the presser the strip passes to the moistener, said co-acting means being movable with the presser to lift the strip positively off the moistener on the strip severance.

10 8. A strip serving apparatus comprising in combination a strip roll support, a moistener, strip severing means mounted above the moistener and to the rear of the moistening point and above the service path of the strip and against which the strip must be lifted for severance, and a strip presser actuated by service draft upon the strip to press the latter into intimate contact with the moistener and having provisions for effecting movement of the strip away from the moistener and toward the severing means.

15 9. A strip serving apparatus comprising in combination a strip roll support, a moistener, strip severing means mounted above the moistener and service path of the strip and against which the strip must be lifted for severance, and a strip presser actuated by service draft upon the strip to press the latter into contact with the moistener and having provisions for effecting movement of the free end of the strip away from the moistener and for supporting it in grasping position between and out of contact with the moistener and severing means.

20 10. A strip serving apparatus comprising in combination, a strip roll support, a moistener, a movably mounted strip presser actuated by service draft upon the strip to press the latter against the moistener, and a moisture excluding shield and strip lifter movable with the presser.

25 11. A strip serving apparatus comprising in combination, a strip roll support, strip severing means at one side of the service path of the strip, strip moistening means at the other side of said service path, and means actuated by service draft upon the strip to press the strip into effective contact with the moistener, and having provisions for moving the strip toward the severing means.

30 12. A strip serving apparatus comprising in combination a strip roll support, a moistener co-operating therewith, a pivoted strip

35 directing member having a strip presser and a perforated shield 34 having a deflected edge 34'.

13. A strip serving apparatus comprising in combination, a strip roll support from 40 which a strip may be drawn by the hand of the operator, a moistener having means to present a thin film of liquid to the strip and to prevent the presentation of liquid in excess of said film, strip severing means, a strip presser actuated by draft upon the strip to press the latter when drawn upon into intimate engagement with said liquid film, and a combined guard and strip lifting device movable with the strip presser and acting positively to elevate the strip from the moistener.

14. A strip serving apparatus comprising in combination, a strip roll support, a rotatable moistener having a non-absorbent 45 periphery, means co-operating therewith to present a thin film only of moisture to the strip, a pivoted strip presser, and a strip lifter movable with but spaced from the presser and between which and the presser the strip passes into operative relation to the moistener.

15. A strip serving apparatus comprising in combination, a strip roll support, a rotatable moistener having a non-absorbent 50 periphery, means co-operating therewith to present a thin film only of moisture to the strip, a pivoted strip presser, and a combined strip guard and lifter movable with the presser but spaced therefrom, and a fixed severing blade at a higher elevation than the moistener and against which the strip may be drawn by elevation of the presser and lifter.

16. A strip serving apparatus comprising in combination, a strip roll support, a moistener, strip severing means positioned above the service path of the strip and against which the strip is adapted to be lifted, a strip presser pivoted adjacent the moistener and under which the strip is adapted to be passed in its service path, whereby the strip may be positively pressed into intimate engagement with the moistener, and a strip shielding and lifting member movable with the presser and mounted at the under side of the service path thereof.

17. A strip serving apparatus comprising in combination a strip roll support, a moistener, a pivotally mounted strip presser actuated by service draft upon the strip to press the latter against the moistener, and a combined moisture excluding and strip guiding member co-operating with the presser.

18. A strip serving apparatus comprising in combination a strip roll support, a moistener co-operating therewith, a strip directing member having a moisture excluding shield and a strip presser positioned in proximity to the moistener and adapted upon

- service draft upon the strip to press the latter in intimate moistening relation to the moistener.
19. A strip serving apparatus comprising in combination a strip roll support, a moistener coöperating therewith, a strip directing member having a moisture excluding shield and a grooved strip presser movable to and from the moistener.
- 10 20. A strip serving apparatus comprising in combination a strip roll support, a moistener, a pivotally mounted strip presser actuated by service draft upon the strip to press the latter against the moistener, and a strip 15 guiding member mounted to move with the presser and having an edge adapted to engage the strip and to discharge or deflect moisture therefrom.
21. A strip serving apparatus comprising 20 in combination, a strip roll support, a moistener, strip severing means positioned above the service path of the strip against which the strip is adapted to be lifted, a strip presser mounted closely adjacent to the moistener, and moved by service draft to press the strip against the moistener and movable with the strip for strip severance, and a strip lifting and shielding member movable with the presser.
22. A strip serving apparatus comprising 30 in combination, a strip support from which a strip may be drawn by the hand of the operator, a non-absorbent moistener having means to present a thin film of liquid to the strip, strip severing means, and a strip 35 presser actuated by draft upon the strip to press the strip when drawn upon into intimate engagement with said liquid film.
23. A strip serving apparatus comprising 40 in combination, a strip roll support, a moistener, a severing blade above the service path of the strip and against which the strip may be deflected for severance, and a strip presser between the moistener and severing blade 45 and constructed and arranged to engage the strip and to press it into contact with the moistener during strip service and to position the free end of the strip after severance in grasping position between and out of contact with the moistener and severing blade. 50

In testimony whereof, I have signed my name to this specification, in the presence of two subscribing witnesses.

THEODORE M. FOOTE.
